ARTHUR CECIL BUTLER, OF BOSTON, MASSACHUSETTS.

DRAWING OR DRAFTING MECHANISM.

Application filed December 8, 1921. Serial No. 520,869.

To all whom it may concern:

Be it known that I, ARTHUR CECIL BUTLER, a subject of the King of Great Britain, residing at Boston, in the county of Suffolk 5 and State of Massachusetts, have invented new and useful Improvements in Drawing or Drafting Mechanism, of which the following is a specification.

This invention has relation to drawing or 10 drafting mechanisms for fibrous materials such as may be employed in drawing or spinning frames, and has for its object to provide a mechanism by which the sliver or roving may be greatly attenuated and elongated 15 without the formation of bunches or thin and thick spots.

Ordinarily, when a sliver or roving is presented to the drawing rolls, the pairs of rolls, which are driven at increasing speeds from 20 the rear to the front, are separated from each other far enough to accommodate fibers of the greatest length which occur in the roving, and it frequently occurs that bunches of 25 relatively short fibers are carried along with the longer fibers by the nip of the rolls so as to form bunches in the resulting drawn sliver or roving.

The object of this invention is to provide 30 means by which the fibers are properly presented to the rolls and the shorter fibers retarded more or less so as to prevent the formation of bunches and ensure the delivery 35 of a sliver or roving which is substantially free from thin and thick spots.

On the accompanying drawing,—

Figure 1 illustrates a drawing or drafting mechanism embodying the invention.

Figure 2 represents the instrumentalities 40 located between two adjacent pairs of drawing rolls in the mechanism shown in Figure 1.

Figure 3 represents another form of drawing mechanism embodying the invention.

Figure 4 shows one of the cap plates engaging 45 an intermediate roll such as employed in the mechanism shown in Figure 3.

Figure 5 shows conventionally a plurality of disks which may be utilized with one of the grooved rolls in lieu of the cap plate.

Referring more particularly to Figure 1, 50 —10 indicates a roll stand which is provided with the three pairs of drawing rolls 11, 12, 13, 14 and 15, 16, which may take the usual form employed in spinning or drawing frames. The top rolls 11, 13 and 15 may be shod with leather or other frictional material, and the bottom rolls 12, 14 and 16 may

be fluted as ordinarily. The lower rolls of the pairs may be driven as ordinarily except that they may be respectively rotated to secure a greater draft or attenuation of the 60 roving or sliver than heretofore. In passing from one pair of rolls to the next forward pair, the sliver or roving is elongated and attenuated. Any usual means may be employed for adjusting the pairs of rolls 65 towards and from each other, and I have illustrated conventionally an adjustable bracket 17 mounted on the roll stand so that the rolls 13 and 14 may be adjusted towards or from the rolls 11 and 12. A similar 70 bracket 18 may be utilized for supporting the rolls 16 and 15 and for permitting their adjustment towards and from the rolls 13 and 14. These parts are all shown more or less conventionally, and I have not shown the 75 usual weighted saddles or the means for maintaining the rolls 11, 13 and 15 in place, such parts forming no particular feature of the present invention. In Figure 1, I have illustrated one embodiment of the invention, 80 which comprises a pair of members for ensuring the proper delivery of the sliver or roving to the drawing rolls in front thereof. It will be observed that in this case I employ 85 for the rolls 13 and 14 a roll 19 which is provided with circumferential grooves 20, 20, and that for cooperation with this roll I employ disks 21 on shaft 22. The disks enter the grooves 20 of the roll 19 and rest preferably by gravity upon the slivers or rovings 90 which pass over the bottom walls of the grooves. The journals at the ends of the roll 19 may rest in appropriate bearings formed in the bracket 18, in which the roll 16 is journaled, so that the rolls 19, 16 are 95 adjusted simultaneously. For cooperation with the rolls 11 and 12, I employ, in Figure 1, another pair of rotary members similar to those shown in Figure 2, which are indicated respectively at 23 and 24, the shaft for the 100 disks 24 being in this case indicated at 25. The journals at the end of the grooved roll 23 rest in bearings afforded by the bracket 17 in which the roll 14 is journaled. A sliver or roving, after passing the nip of the 105 rolls 15, 16, passes between a disk 21 and the bottom of the groove of the roll 19 to the intermediate drawing rolls 13 and 14. The lower roll 19 is preferably so driven that the peripheral speed of the bottom wall of its 110 groove is equal to the peripheral speed of the rear bottom roll 16; or, if desired, it may

be driven at a slightly higher speed. As the roving or sliver is gripped by the rolls 13 and 14, it is drawn forward and is elongated or attenuated, but the engagement of the 5 disks 21 and the roll 19 with the sliver or roving prevents loose short fibers from being drawn along in bunches with the tips of the long fibers engaged by the rolls 13 and 14. The roving, however, is carried along by 10 frictional contact of the disk and the bottom and side walls of the groove in the roll 19. The disks rest by gravity on the sliver or roving and serve to compress them in the groove 20 and also in conjunction with the side walls 15 of the groove to condense and compact them. The groove thus serves to assist in concentrating the fibers of the roving and acts as a guide so that the fibers do not spread laterally and become detached after passing between the rolls in the rear thereof.

As a result of this construction, only the fibers actually seized by the drawing rolls in front of the grooved roll and the disks are drawn out, and consequently the short 25 fibers are separated much more regularly than would be possible if they were permitted to be dragged along with the sliver or roving. The action of the disks 24 and the roll 23 is the same as that described in 30 connection with the disks 21 and the roll 19. In this case, the disks rest by gravity on the sliver in the grooves of the roll 23, the latter roll preferably being driven so that the peripheral speed of the bottom wall of the 35 groove therein is substantially equal to or slightly greater than the peripheral speed of the intermediate bottom roll 14.

It will be understood that the top disks are not weighted but rest lightly on the 40 roving with just sufficient pressure to compress the roving or sliver into the groove and permit the fibers to be drawn from under it by a pair of rolls immediately in front. Inasmuch as the disks and their cooperating 45 grooved rolls are of small diameter, they may be set close to the pair of rolls immediately in front thereof.

It is not essential that the members, which 50 cooperate with the grooved rolls, should of themselves be rotatable as they might have a sliding engagement with the grooved rolls and the slivers which lie in the grooves thereof. In Figure 3, I have shown for example a construction in which, instead of employing 55 three pairs of drawing rolls, I utilize the front and rear pairs but substitute for the intermediate pair a relatively large roll which is grooved circumferentially and with which non-rotary members are utilized to 60 enter the grooves thereof and engage the slivers or rovings lying therein. In this case, the front rolls are indicated at 26 and 27, and the rear rolls are indicated at 28 and 29. In this case, instead of employing 65 leather-shod top rolls and fluted lower rolls,

the lower rolls 27 and 29 may be circumferentially grooved as indicated and the top rolls may be in the form of disks to enter such grooves and rest on the slivers or rovings therein. In this case, however, the top 70 rolls may be fluted or milled or they may be shod with some frictional material at will. Indeed in some cases the bottom walls of the grooves of the rolls 27, 29 may be fluted or milled. Between the two pairs of rolls 75 26, 27 and 28, 29, I interpose a relatively large roll 30 which is driven at a speed greater than that of roll 29 and less than that of roll 27. In fact, the three rolls 29, 30 and 27 are driven at the desired speeds 80 relatively to each other to effect a long draft of the sliver or roving. Associated with the roll 30, there is a cap plate 31, the lower edge of which is arcuate and complementary to the curvature of the bottom wall of the 85 groove 33 in the roll 30, as shown in Figures 3 and 4. This plate is illustrated as set edgewise so that it will enter the groove 33, and it is provided with arms 34 by which it may be hung on a suitable pivot. The plate 90 rests loosely by gravity on the sliver or roving in the groove of the roll 30 and compresses it into the bottom of the groove, so that (while the roving or sliver is carried forward by frictional contact with the bottom of the groove and to some extent by the side walls of the groove, which together may have more hold upon it than the smooth edge of the plate 31, so that the tips of the fibers forming the end of the roving are fed to 100 the nip of the front rolls 26 and 27) the short fibers are retarded and separated so as to prevent bunches thereof from being drawn forwardly by the rolls 26 and 27. I also utilize, in connection with the intermediate roll 30, a preferably weighted disk roll 105 which comprises a shaft 35 and disks 36 arranged to enter the grooves of the roll 30 and rest loosely upon the slivers or rovings therein, and in such case the hooked ends of the arms 34 may engage the shaft 35 which thus serves as a pivot or pintle about which the plate 31 may move. Between the intermediate rolls 30, 36 and the rear rolls 28, 29, I may utilize a grooved 110 roll 37 and a disk roll consisting of a shaft 38 and disks 39 thereon for entering the circumferential grooves of the coating roll 37. In fact, these instrumentalities indicated at 37, 38 and 39 may be substantially 115 like those indicated at 19, 21 and 22 as shown in Figure 2. Preferably the roll 37 is so driven that the peripheral speed of the bottom wall of its groove is approximately equal to or slightly greater than the peripheral speed of the bottom wall of the groove in the roll 29.

Instead of employing the cap plate 31 in cooperation with the roll 30, I may employ a plurality of small disk rolls 40, 41 and 42, as 120

shown in Figure 5. These disk rolls, being small, may be placed fairly close together and all of them enter the same groove in the roll 30 so as to rest by gravity on the sliver or roving therein.

Referring once more to Figure 3, I have shown more or less conventionally how the roll 30 may be journaled in a tilting frame 43 pivoted at 44 to the roll stand 45. In this case, the frame may be adjusted around its pivot by an abutment screw 46. The roll 29 may be mounted on an adjustment bracket 47 supported by the frame 43. I have also indicated more or less conventionally in dotted lines at 48 a cap bar such as may be utilized in holding the shafts for the disk rolls 28, 39 and 36 in proper relation to the bottom rolls associated.

A construction, such as illustrated in Figures 3 and 5, differs from that shown in Figure 1 in that in the latter the roving travels in substantially a straight line from the nip of the back rolls 15, 16 to the nip of the rolls 13, 14, and therefrom to the nip of the rolls 11 and 12. In Figures 3 and 5, however, the intermediate roll 30 is so located in reference to the rolls 26 and 27 and the rolls 37, 39 (or the rolls 28, 29) that it projects beyond a straight line connecting the nips of these rolls, and consequently the roving is caused to engage an elongated portion of the bottom of the groove in the roll 30 and thereby travel in an arcuate path. The engagement of the roving, not only with the bottom but also with the sides of the grooves, tends to retard the passage of the loose fibers with those longer fibers, the ends of which are nipped by the rolls 26, 27. In some instances, by reason of this arrangement, I am able to dispense with any coacting member to press upon the roving which lies in the groove.

In case the usual pairs of drawing rolls are employed as in Figure 1, wherein the upper rolls are covered with friction material, I contemplate traversing the pairs of grooved and disk rolls transversely of the movement of the slivers or rovings, and this is easily accomplished by reciprocating the lower rolls, 19, 23 axially by means for the usual traversing mechanism employed in drawing or spinning frames. The axial movement of the lower grooved rolls of course causes a like reciprocation of the coacting disk rolls, since the disks are engaged with the grooves of the lower rolls.

Having thus explained the nature of my said invention and described a way of making and using the same, although without attempting to set forth all of the forms in which it may be made or all of the modes of its use, what I claim is:—

1. A drawing mechanism comprising two

pairs of drawing rolls and means arranged between them to retard the passage of short fibers with the sliver or roving, said means including a roll having a circumferential groove to receive the sliver or roving, and a member engaging the groove and pressing against the sliver or roving therein.

2. A drawing mechanism comprising two pairs of drawing rolls and means arranged between them to retard the passage of short fibers with the sliver or roving, said means comprising a driven roll having a circumferential groove to receive the sliver or roving, and a non-driven member engaging the groove and pressing against the sliver or roving therein.

3. A drawing mechanism comprising two pairs of drawing rolls and means arranged between them to retard the passage of short fibers with the sliver or roving, said means comprising a roll having a circumferential groove, and a non-rotary arcuate member engaging said groove and pressing against the sleeve or roving in said groove.

4. A drawing mechanism comprising a circumferentially grooved roll having its groove adapted to receive the roving or sliver, and a member engaging said groove and pressing against the sliver or roving therein.

5. A drawing mechanism comprising a circumferentially grooved roll having its groove adapted to receive the roving or sliver, a rotary member engaging said groove and pressing against the sliver or roving therein, and a non-rotary member slidingly engaging said groove and the roving or sliver therein.

6. A drawing mechanism comprising a circumferentially grooved roll having its groove adapted to receive the roving or sliver, and a plurality of members each engaging said groove and pressing against the sliver or roving therein.

7. A drawing mechanism comprising a circumferentially grooved lower roll and a disk roll engaging the groove of the lower roll.

8. A drawing mechanism comprising two pairs of rolls spaced apart in the direction of the travel of the roving or sliver, and an intermediate roll located between said pairs of rolls and having a peripheral groove to receive the roving, said intermediate roll being arranged to project beyond a line connecting the nips of said pairs of rolls, whereby the roving engages the bottom and sides of the groove while traveling in an arcuate path.

In testimony whereof I have affixed my signature.

ARTHUR CECIL BUTLER.
